DRAFT ATTACHMENT

Application filed January 19, 1927. Serial No. 161,992.

Fig. 1 is a horizontal section showing an embodiment of our invention intended for use with Farlow attachments; Fig. 2 is a vertical section thereof on line II—II of Fig. 1; Fig. 3 is a section similar to Fig. 1, but with the coupler under draft and pulling at an angle to the draft attachments; Fig. 4 is a perspective of the buffer block; Fig. 5 is a section showing the application of our invention to a vertical hooded yoke; Fig. 6 is a section on line VI—VI of Fig. 5; and Fig. 7 is a section showing the application of a modified form of intermediate follower particularly adapted for use in connection with a vertical yoke.

With the present day modern heavy service requirements, difficulty is had with either of the two types of draft attachments now in most common use, i. e., vertical and horizontal yokes, for the reason that neither of these attachments in its connection with the standard shank of the standard D-coupler contains any adequate provision for lateral angling of the coupler relative to the means by which it is attached to the car. While the standard coupler shank and attachments provide for a lateral movement of the coupler head of $1\frac{3}{4}$ inches on either side, measured at the face line of the striking casting, the horizontal yoke and the standard vertical yoke can not move laterally more than a fraction of an inch, with the result that on a curved track the entire draft stress will be thrown upon and carried through only one side of the yoke. This also results in a very unequal distribution of stress through the sides of the coupler shank to and through the horizontal draft key. American Railway Association standards call for a minimum of 12 square inches cross section of metal in tension through the coupler and attachments, but when the coupler is angled laterally so that the pull is only through one side of the yoke, it is obvious that only one-half of the capacity of the yoke is available

and that the attachments thus do not comply with the said standards. As the rear face of the standard D-coupler shank is square, it is clear that it will have only a line bearing upon the front follower when the coupler is angled. When the coupler is angled to its fullest extent, this line bearing will be off-centered $2\frac{5}{8}$ inches, or one-half the width of the coupler shank, with the result that the wedge or friction elements of the draft gear may be tipped by this off-centered application of force, which will prevent the gear from offering its full normal resistance to the buffing blow. As buffing shocks are more severe than draft shocks, the gear when the coupler is angled is thus at a great disadvantage and is unable fully to protect the car.

We have devised an improved draft attachment which obviates the difficulties referred to above and gives a true equalized pulling and buffing action when the coupler is angled laterally. In addition we have so formed our attachments that they may be used with either existing vertical or horizontal yoke or links without change in the yoke or links, and permit just as great lateral angling as with present devices. It also permits the use of the present standard D-coupler as a repair or replacement in such a way as to meet the American Railway Association standards as to strength, safety, etc., and further has the advantage of reducing to a minimum the additional weight as well as the cost of the additional parts required. Our invention also comprises various features which we shall hereinafter describe and claim.

Referring to the drawings, we have shown our invention applied to a car coupler secured to a car by the usual Farlow attachments, in which A indicates the car coupler, B the horizontal links or yoke arms, C the draft gear, D the draft key, which extends through horizontal slots 2 in the links and 3 in the coupler shank, and E the front fol-

lower, with its key F. The slot 3 in the coupler shank has its front face 4 bevelled forwardly on each side of the coupler center line and its rear face 5 is concave in a horizontal plane. Both front and rear surfaces 4 and 5 are also concave in vertical planes. Seated in the concave face or bearing 5 is an equalizer member 6, the rear face 7 of which is convex in two directions to correspond with the surface 5, and its forward face 8 is concave in a vertical direction. The rear end of the coupler shank has an arc-shaped rear surface 9, preferably struck about the same center as the bearing 5. Between the arc-shaped rear end 9 of the shank and the front face of the follower E is the buffering block 10, the forward face 11 of which is curved in approximately the same arc as the surface 9. Integral with and extending forward from the follower E are the wings 12 between which is seated the buffering block 10. These wings 12 preferably flare outwardly and extend a sufficient distance forward to act as lateral guides for the coupler shank particularly during return from the draft movements of the shank. At its upper and lower portions the buffering block 10 has forwardly extending webs 13 which lie above and below the coupler shank and act to guide or restrain the shank vertically in its draft movements. As is shown in Fig. 3, these webs 13 extend forwardly far enough to overlap the rear end of the shank in its extreme forward movement. The webs 13 also extend laterally so as to overlap the top and bottom of the wings 12 of the follower E, so that the follower E accordingly supports the buffering block. It may be held in such position by cotters 14 or the like extending in front of the ears 15 on the top and bottom webs 13.

When the coupler is angled laterally the shank will rotate about the convex bearing 7 on the equalizing member 6. When under draft, the shank will have an extended bearing on the key D through the equalizing member 6, and the key D will have an equalized bearing on the forward sides of the yoke arms B at the forward ends of the slots 2, thus transmitting to the draft gear C through the yoke arms B the equalized load. Under buff, when the coupler is angled laterally the arc-shaped rear end 9 of the coupler A will strike the curved forward face 11 of the buffering block 10. If the angled movement of the coupler is extreme, the rear end of the coupler will first strike the wings 12 and then slide into engagement with the arc-shaped face 11 of the buffering block 10, and will drive the buffering block 10 and front follower E rearwardly against the resistance of the draft gear. It will thus be seen that as the coupler shank is driven rearwardly under buff, the wings 12 of the front follower E and the curved face 11 of the buffering block 10 will tend to center and guide it, so that an off-

centered application of force will not be applied to the draft gear.

In Figs. 5 and 6 we have shown our invention applied to a standard vertical hooded yoke J shown in connection with the usual draft sills K, front draft lugs L, and a single horizontal key M. The buffering block 20 has its top and bottom webs or walls 23 carried well forward, so that when the coupler is under draft the block will be amply supported by the shank. It is not necessary here to provide the forwardly flaring wings upon the front follower N, for the reason that the sides 22 of the yoke hood closely confine the movement of the coupler A. These side walls 22 of the yoke hood also have the advantage of preventing the buffering block 20 from twisting within the hood. If desired, projections 25 may be added at the top and bottom of the buffering block so that it will be further supported by the yoke arms.

In Fig. 7 we have shown a modified form of yoke in which the vertical dimension (indicated at a—a) at the forward end of the yoke hood is increased so as to make the opening of a slightly greater vertical extent than the vertical height of the buffering block, so that the buffering block may be readily applied or removed through the forward end of the hood.

It will be seen that in our improved construction the coupler shank from the forward end of the slot 3 forward conforms to the present D-coupler standard, but rearwardly of this point the shank is flared out to a width of approximately 6 inches to compensate for the loss of metal due to the increase in size in the key slot. Rearward of the line b—b the sides of the shank are bevelled off slightly, in order to allow it to swing sufficiently in the vertical yoke.

As it is practically an essential that the standard D-coupler may be interchangeable with the special shank coupler here shown, we have so constructed our shank and the buffer block that the distance from the forward face of the equalizer 6 to the rear face of the buffer block is the same as the distance from the rear face of the key slot in the shank of the standard D-coupler to the rear end of such shank. In case of coupler breakage, the broken coupler with its equalizer may be withdrawn from the yoke, the buffering block removed and a standard D-coupler applied, resulting in the usual standard application either to a Farlow attachment or to a standard vertical hooded yoke, as the case may be.

Our invention provides in the draft equalizer block means by which an equal pull at all times is imposed upon the arms of the yoke and at the same time permits the draft key to angle freely in the coupler shank, thereby equalizing the pulling stresses within the shank as well as the pulling stresses upon the key. As the arc-shaped rear end of the cou-

pler shank seats against a correspondingly shaped surface in the buffering block, there is likewise provided an equalized bearing against the follower in buffering, thereby preventing any tendency for the follower to angle laterally as it is buffed against the gear, and consequently the gear is pressed evenly, with no tendency to tip the follower wedge or elements of the gear.

- 10 The terms and expressions which we have employed are used as terms of description and not of limitation, and we have no intention, in the use of such terms and expressions, of excluding any mechanical equivalents of 15 the features shown and described, or portions thereof, but recognize that various structural modifications are possible within the scope of the invention claimed.

What we claim is:

- 20 1. In a coupler attachment, the combination of a coupler shank and a yoke having horizontal aligned slots; a connecting key seating in said slots; a draft gear in said yoke; a follower for said gear; and a buffering block removably supported by said follower having a rotative engagement with said shank.

25 2. In a coupler attachment, the combination of a coupler shank and a yoke having horizontal aligned slots; a connecting key seating in said slots; a draft gear in said yoke; a follower for said gear; a buffering block removably supported by said follower having a rotative engagement with said shank; and means movable relative to said coupler in draft for guiding the rear end of said coupler into engagement with said buffer in the central vertical plane thereof.

30 3. In a coupler attachment, the combination of a horizontally slotted coupler shank having a curved rear face in said slot and a curved rear face upon the exterior thereof; a horizontally slotted yoke; a horizontal key extending through said horizontal slots in said shank and yoke; a draft gear mounted in said yoke; a buffering block having a supporting engagement with the draft gear, said block having an overlapping engagement in buffering and in draft with the coupler shank.

35 4. In a coupler attachment, the combination of a horizontally slotted coupler shank having a curved rear face in said slot and a curved rear face upon the exterior thereof; a horizontally slotted yoke; a horizontal key extending through said horizontal slots in said shank and yoke; a draft gear mounted in said yoke; a follower of said gear; a buffering block intermediate said follower and coupler end, said follower having forwardly extending wings arranged to guide the coupler butt into engagement with said buffering block.

40 5. In a coupler attachment, the combination of a coupler shank and a yoke having horizontal aligned slots; a connecting key seating in said slots; a draft gear in said yoke; a fol-

lower for said gear; a buffering block removably supported by said follower having a rotative engagement with said shank; and means for holding the buffering block in operative relation between shank and follower.

45 6. In a coupler attachment, the combination of a coupler shank and a yoke having horizontal aligned slots; a connecting key seating in said slots; a draft gear in said yoke; a follower for said gear; a buffering block intermediate said follower and shank; and side members within the yoke forward of said follower having a supporting engagement with one of said parts and being arranged to 50 guide the coupler butt into engagement with said buffering block.

55 7. In a coupler attachment, the combination of a coupler shank, a horizontal yoke, and a follower, means for connecting said shank and yoke for transmitting draft stresses, a buffering block between the rear end of said shank and said follower and movable radially with respect to the shank, and guiding means carried by one of said members adjacent the rear end of the shank for guiding said shank into alignment with said follower.

60 8. In a coupler attachment, the combination of a coupler shank, a horizontal yoke, and a follower, means for connecting said shank and yoke for transmitting draft stresses, a buffering block between the rear end of said shank and said follower and movable radially with respect to the shank, and guiding means carried by one of said members disposed laterally of the shank near the rear end thereof for guiding said shank into alignment with said follower.

65 9. In a coupler attachment, the combination of a coupler shank and a yoke secured together by a horizontally extending key; a draft gear mounted in said yoke; a follower for the draft gear; a block between the rear end of the coupler shank and the follower removably supported on one of said members, said block being operative only in buff and means cooperating with said shank and positioned between the arms of said yoke for bringing the rear end of the shank into central bearing on said block during return of the shank from draft position.

70 10. In a coupler attachment, the combination of a horizontally slotted coupler shank, having a curved rear face in said slot and a curved rear face upon the exterior thereof; a horizontal key within said horizontal slot; cushioning mechanism rearward of said shank; a follower interposed between said cushioning mechanism and shank; and independent stress equalizing members supported independently of the yoke interposed between said curved faces and said key and said follower for transmitting draft and buffering stresses from said shank to said cushioning mechanism, one of said equalizing members

being movable relative to said follower and with said shank in draft and the other of said members being movable in buff relative to said yoke and with said first named equalizing member.

11. In a coupler attachment, the combination of a coupler shank and a yoke having horizontal aligned slots; a connecting key seating in said slots; a draft gear in said yoke 10 and a follower between said gear and coupler shank, and independent draft and buff equalizing members, one of said members seated within said shank and bearing upon said key and the other of said members being interposed between said shank and follower and being movable rearwardly relative to said yoke in buffing, whereby said yoke may remain stationary during buffing movements of said coupler.

12. In a draft rigging, the combination with a coupler having a shank of the same vertical height throughout its length, of a cast hooded yoke having the upper and lower walls of the hood section thereof forwardly converged, and within which hood section the butt end of the coupler shank is adapted to be received; a shock absorbing device having front follower acting means; and removable means occupying each of the spaces left 20 between and defined by the front face of said follower acting means, converging wall of the hood section, and opposed horizontal surface of the coupler shank and held in place by said follower.

13. As an article of manufacture, a front follower for a railway draft rigging having a follower section proper transversely slotted to receive a key, and upper and lower fixed jaws projecting forwardly therefrom, said jaws being spaced to fit over the butt end of a coupler shank.

14. In a railway draft appliance, the combination with a slotted yoke having a plurality of spaced arms adapted to receive a cushioning device between them, of a car coupler having a slotted stem extending into said yoke, a key passing through said slots for slidably connecting the yoke and coupler, and a bearing block floatingly mounted in said yoke for transmitting buffing force to a cushioning device, said coupler and bearing block being longitudinally movable with respect to the yoke during buffing, said bearing block having portions overlappingly embracing opposite sides of the stem of the coupler in all positions the latter may assume in draft, and said coupler stem and bearing block being provided with correspondingly curved cooperating bearing surfaces permitting the coupler to swing with respect to said block.

15. In a railway draft appliance, the combination with a slotted yoke having a plurality of spaced arms adapted to receive a cushioning device between them, of a car coupler having a slotted stem extending into

said yoke, a key passing through said slots for slidably connecting the yoke and coupler, the slots of the yoke being elongated to permit the coupler to move rearwardly with respect to the yoke in buffing, a key seat member interposed between the coupler and the key, and a floating bearing block engaging the rear end of the coupler and movable longitudinally with respect to the yoke in buffing, said coupler being provided with a plurality of concentrically curved surfaces, said key seat being provided with a curved face for cooperating with one of the curved surfaces of the coupler, said bearing block being provided with a curved surface for 70 cooperating with the other curved surface of the coupler and also being formed with forwardly extending portions embracing opposite sides of the coupler, said forwardly extending portions having inclined forwardly 75 converging faces, and the said yoke being provided with correspondingly inclined faces adapted to cooperate with the bearing block to form guides for the latter.

16. In a draft rigging, the combination with a coupler having a shank of the same vertical height throughout its length, of a cast hooded yoke having the upper and lower walls of the hood section thereof forwardly converged, and within which hood section the butt end of the coupler shank is adapted to be received; a shock absorbing device having front follower acting means; and removable means positioned in each of the spaces left between and defined by the front 100 face of said follower acting means, converging wall of the hood section, and opposed horizontal surface of the coupler shank and held in place by said follower, all portions of said removable means being within the 105 confines of said yoke for enabling said means to move rearwardly with respect to said yoke during buffing movements of said shank.

17. In a coupler attachment, the combination of a coupler shank and a yoke having horizontally aligned slots; a connecting key seating in said slots; a draft gear in said yoke; a follower for said draft gear; a buffing block between the shank and follower operative only in buffing adapted to bring the rear end of the shank into central bearing with the draft gear; and means disposed between the side of the shank and the yoke for guiding the coupler shank laterally.

18. In a coupler attachment, the combination of a coupler shank and a yoke having horizontally aligned slots; a connecting key seating in said slots; a draft gear in said yoke; a follower for said gear; a buffing block interposed between said shank and follower having a rotative engagement with said shank; and guiding means disposed between the sides of the shank and the yoke for guiding the coupler shank laterally.

19. In a coupler attachment, the combina-

tion of a coupler shank and a yoke having horizontal aligned slots, a connecting key in said slots; a draft gear in said yoke; the yoke having walls extending over and under the coupler shank and separate members engaging said shank, one of said members being confined within the shank and active only in draft, the other of said members being supported on the shank and disposed between the shank and draft gear, said latter member being confined entirely between said yoke walls whereby said member may move longitudinally relative to the yoke in buff.
